UNITED STATES PATENT OFFICE.

JOHN L. GROO, OF SALT LAKE CITY, UTAH.

ANTIFREEZING DEVICE FOR WATER-PIPES.

1,265,772.

Specification of Letters Patent.

Patented May 14, 1918.

Application filed March 22, 1917. Serial No. 156,701.

To all whom it may concern:

Be it known that I, JOHN L. GROO, a citizen of the United States, residing at Salt Lake City, in the county of Salt Lake 5 and State of Utah, have invented certain new and useful Improvements in Antifreezing Devices for Water-Pipes; and I do declare the following to be a full, clear, and exact description of the invention, such as will 10 enable others skilled in the art to which it appertains to make and use the same.

My invention has for its object to provide extremely simple means for preventing water from freezing in water pipes exposed to cold temperatures, this end being attained by introducing a salt or other anti-freezing medium to the water as it passes through the pipe.

With the foregoing general object in view, the invention resides in certain novel features of construction and unique combinations of parts to be hereinafter fully described and claimed, the descriptive matter being supplemented by the accompanying 25 drawings which constitute a part of this application and in which:

Figure 1 is a perspective view of the invention applied;

Fig. 2 is an enlarged vertical section 30 thereof;

Fig. 3 is a vertical section on the plane of the line 3—3 of Fig. 2;

Fig. 4 is a horizontal section on the line 4—4 of Fig. 2.

In the drawings above briefly described, P has reference to the vertical pipe of a building designed to conduct water from the usual eavestroughs to any desired point but usually to a suitable container. Here- 35 tofore, in freezing temperatures it has been impossible to prevent freezing of the water in pipes such as P with the result that they become clogged with ice so that the water from the troughs is not properly carried off. This causes these troughs to overflow and the water dripping in this manner as well as that collecting in said troughs is frozen into ice which causes great trouble particularly when thawing begins. The 40 present invention aims to overcome this difficulty by introducing salt or other anti-freezing medium into the water passing downwardly through the pipe. The water treated in this manner will not freeze and since pipes of the character set forth freeze 45 from the bottom up, the conditions above

described cannot be caused. The construction employed for introducing the anti-freezing medium is preferably in the form described below.

A vertical pipe section 1 is interposed between two sections of the pipe P at any desired point above the lower end of the latter, said section 1 being preferably though not necessarily rectangular in horizontal 60 section and having in one of its sides an opening 2 into which a suitable hopper 3 discharges, said hopper being located on the exterior of the pipe section 1 and having a hinged inclined top 4 by means of which it 65 may be filled when required. The lower end 5 of hopper 3 inclines downwardly to the pipe section 1 and is provided on its lower side with a guide or sheath 6 in which a pervious slide 7 is located, the inner end of said slide 75 normally extending across the pipe section 1 to form a pervious support for the salt or the like supplied from the hopper. A suitable ledge 8 is preferably provided in the section 1 to support the inner end of 80 the slide 7.

A gate valve 9 is employed for controlling the amount of salt discharged from the hopper 3, said valve being in the form of a rectangular plate contacting slidably with 85 the exterior of the section 1 and located in said hopper, a suitable stem 10 being provided for operating said valve. The valve 9 is guided in its movement by vertical flanges 11 formed in a unique manner. The 90 two opposed sides 12 of the hopper 3 are bent inwardly upon themselves near their free edges at 13 to form flanges which are soldered or otherwise secured to the sides of the section 1, and after being bent in 95 this manner said edges of the sides 12 are bent inwardly at right angles to form the flanges 11 which are spaced from the section 1.

In use, the pipe section 1 is introduced 100 into the pipe P at a suitable point as indicated in Fig. 1 and the hopper 3 is filled with the anti-freezing medium to be employed, the opening 2 being now controlled by the valve 9 to permit the required amount 105 of salt or the like from the hopper to pass into the section 1 upon the partition 7 therein. Any water now passing downwardly through the pipe will be prevented from freezing since it is converted into a 110 briny solution and whenever required the hopper 3 may be refilled by opening the top

4 thereof. During the warmer months, when the use of the device is not needed, the slide 7 may be easily withdrawn and the valve 9 then closed.

5 From the foregoing, taken in connection with the accompanying drawings, it will be obvious that although the invention is of simple and inexpensive nature, it will be highly efficient for the purpose intended.

10 For these reasons, the construction shown constitutes the preferred embodiment of the device but it is to be understood that within the scope of the invention as claimed, numerous minor changes may be made without 15 sacrificing the principal advantages. Furthermore, the use of the invention is not limited to water pipes such as those described but is applicable to any pipe exposed to freezing temperatures.

20 I claim:

1. The combination with a water pipe having in one side an opening, of a pervious partition extending across said pipe below said opening for supporting an anti-freezing

25 medium therein in the path of the water passing through said pipe, and a hopper on the exterior of the pipe for supplying said medium to said partition through said opening.

30 2. The combination with a water pipe

Copies of this patent may be obtained for five cents each, by addressing the "Commissioner of Patents, Washington, D. C."

having an opening in its side, of a hopper on the exterior of said pipe discharging into said opening, said hopper having an inclined bottom equipped with a guide, and a pervious slide in said guide movable across 35 said pipe to support therein an anti-freezing medium supplied by said hopper.

3. The combination with a water pipe having an opening in its side, of a hopper on the exterior of said pipe for supplying 40 an anti-freezing medium to said pipe through said opening, the opposed sides of said hopper having their inner edges bent inwardly to form attaching flanges secured to the pipe and then again inwardly to form 45 vertical guide flanges located in the hopper and spaced from said pipe, a valve slidably mounted between said pipe and flanges for controlling the aforesaid opening, and means in the pipe for supporting the anti-freezing 50 medium discharged from the hopper.

In testimony whereof I have hereunto set my hand in the presence of two subscribing witnesses.

JOHN L. GROO.
